UNITED STATES PATENT OFFICE.

BRUNO GERHARD POHLMANN, OF SIEMENSSTADT, NEAR BERLIN, GERMANY, AS
SIGNOR TO SIEMENS & HALSKE, AKTIENGESELLSCHAFT, OF SIEMENSSTADT, NEAR
BERLIN, GERMANY, A CORPORATION OF GERMANY.

AMPLIFYING SYSTEM.

Application filed March 26, 1921. Serial No. 455,820.

To all whom it may concern:

Be it known that I, BRUNO GERHARD POHLMANN, a citizen of the German Empire, residing at Siemensstadt, near Berlin, Germany, have invented certain new and useful Improvements in Amplifying Systems (for which I have filed applications in Germany, December 5, 1919; Switzerland, November 4, 1920; Norway, November 19, 1920; Holland, November 9, 1920; France, November 9, 1920; Denmark, November 20, 1920; Sweden, November 1, 1920; England, December 6, 1920; Italy, December 4, 1920), of which the following is a specification.

15 My invention relates to amplifying connections for telephone lines, and the like. In connections of this kind, with translators interpolated between transmitter, amplifier and receiver, it is customary, in order to secure the best efficiency possible, to so select the impedance of the primary coil pertaining to the pre-translator that it is equal to that of the transmitter, and the impedance of the primary coils pertaining to the intermediary and end translators so that it is equal to that of the tube connected into the system, in which case the natural period of the secondary coil (grid winding) is such that it lies within the frequency range of the 20 alternating-currents to be transmitted, causing it to correspond as far as possible to the mean frequency thereof, in order to obtain for the entire frequency range the most favourable amplifying effect possible.

25 However, a connection of the type specified involves the disadvantage of growing more selective in proportion to the number of translators employed, so that, for example, when amplifying speaking currents, 30 any increase of the amplification will cause speech to become more and more distorted and finally entirely unintelligible.

In the drawings affixed to this specification and forming part thereof, various modifications of electrical connections embodying my invention are illustrated diagrammatically. In these drawings—

35 Figures 1 to 3 show the amplifying curves for one or more amplifiers inductively coupled;

40 Figure 4 shows an amplifying connection embodying a single amplifier tube;

45 Figure 4^a shows a modification of the dampening means arranged in parallel to the

secondary of the translator U shown in Figure 4;

50 Figure 5 shows an amplifying connection in which three amplifier tubes are disposed in series; and

55 Figure 6 shows a modification thereof.

The conditions prevailing for the transmission of the speaking currents are illustrated in Fig. 1 of the drawings. In this figure the numerals I, II and III indicate the amplifying curve for one, two or three 60 amplifying tubes coupled by transformers to the line respectively to each other. On the diagram the abscissæ represent the frequency and the ordinates the amplification of the speaking current represented by milli- 65 amperes.

70 The curves of Fig. 1 show the amplification when the selectivity of the transformers corresponds, as usual, to the frequency 5000. The curve I shows the distortion by the 75 transformer after the passage of the currents through the first transformer, the curve II the distortion after the passage of the second, and the curve III the distortion after the passage of the third transformer. It 80 is assumed that after each passage through a transformer the currents are amplified by 85 amplifying tubes.

It is the object of my invention to minimize this distortion and also those resulting 90 from the line itself. This object may be attained in accordance with my invention in connecting capacities in parallel with the secondaries of the transformers chosen so as to distribute the selectivity of the several 95 90 transformers over the whole range of frequencies for the purpose of influencing the curve of amplification in such a manner as to obtain an elimination of distortion over the whole range of frequencies.

100 In addition to the capacities preferably also resistances are connected in parallel to the secondaries of the transformers in order to diminish the selectivity of the one or the other transformer if necessary.

105 As may be readily understood the frequency corresponding to the natural frequency of the secondary coil and transmitted with the least possible loss will be the one that will be most damped when connecting an ohmic resistance in parallel to the transformer. The effect of the ohmic resistance connected in parallel to the secondaries of a

transformer thus consists in a proportionate reduction of the maximum of the amplifying curve, which again means a reduction of the selectivity and thus of the distortion of the speaking currents by this selectivity. This effect of the ohmic resistance connected in parallel to the secondaries of the transformers is shown in Fig. 2, which represents three amplifying curves I, II, III corresponding to the amplifying curves I, II, III according to Fig. 1. The selectivity of the transformers is in both cases the same, but in Fig. 2 ohmic resistances are connected in parallel to the secondaries of the transformers for attenuating the selectivity of the transformers.

By ohmic resistances connected in parallel with the secondaries of the transformers it is however not possible to eliminate the selective character of the amplifying arrangement and to eliminate the distortion due to the line itself.

According to the invention this object is accomplished by tuning the different transformers to different appropriated frequencies within the range of speaking currents. The effect obtainable thereby is represented in Fig. 3. The curves I', II', III' of this figure correspond to the use of one, two, and three transformers and amplifying tubes, the transformers having each another selectivity. According to the curve I' the preferred frequencies are the mean frequencies in the neighborhood of 5000. The curve II' corresponds to a transformer the selectivity of which corresponds to the lower frequencies, say about 3000, and the curve III' corresponds to the passage of the speaking currents through a third transformer the selectivity of which corresponds to the higher frequencies, say about 7000. The unevenesses in the curve III' may be attenuated for instance by putting an ohmic resistance in parallel to the secondary of the third transformer.

Of course the distortion of the speaking currents caused by the impedance of the wave line may also be considerably attenuated by an appropriate choice of the selectivity of the transformers and the damping of the same. This result is obtainable by a suitable combination of capacities and ohmic resistances.

The different degree of selectivity on the part of the translators may be secured, in accordance with my invention, in an extremely simple manner by connecting suitable condensers in parallel to the secondary coils of the translators. The effect hereby obtained is disclosed, for example, by the curves according to Figs. 1 and 3, of which Fig. 1 indicates the successive amplifier curves for a three-stage amplification in which all the translators obtain their natural period at an average frequency of about 5000. In Fig. 3, curve I' indicates the degree of amplification secured when using a single tube. The pre-translator possesses a natural period of 5000. This particular curve is similar to curve I in Fig. 1. Curve II' shows the amplification obtained when interconnecting a second tube, the pre-translator possessing a natural period of 5000 and the translator intermediate the two tubes one of 3000. The advantage resulting from curve II' relatively to curve II according to Fig. 1 will be readily understood. The lower frequencies show about the same degree of amplification as the mean frequencies. Again, when employing a third tube, the translator of which is tuned to a frequency of about 7000, the curve resulting is that indicated by III'. From this will be seen, that the various frequencies have been amplified to an approximately like degree and that therefore distortion is avoided to a considerable extent.

From the aforesaid it will further be seen that by a suitable selection of the natural periods of the translators the tone colour may be influenced by giving the preference to the higher or lower frequencies, as may be deemed expedient for a given case, and that any further distortions due to other causes than those produced by the translators, may be conveniently removed by allowing for a suitable degree of selectivity on the part of the translators.

In such cases where by a distribution of the natural periods of the translators over the entire frequency range an adequately uniform frequency curve is nevertheless not obtainable, it will be found expedient to combine the suitable distribution of the selectivity over the entire frequency range with a damping of the selectivity. If it be desired that very high degrees of amplification shall be secured, then preferably the natural capacity of the secondary winding is used as a capacity, the number of turns of this winding being so dimensioned that any degree of frequency required will be obtained.

Fig. 4 illustrates an amplifier connection having only a single amplifier tube, in the case of which, in accordance with my invention, a resistance W is connected in parallel to the secondary coil S of the translator U, the said resistance serving to damp the frequencies transmitted. No special damping means are required to be inserted for the supplementary translator N, since the primary winding P₁ is adapted to the resistance of the tube R and the secondary winding S₁ to the receiver T, so that it will act but feebly selective. In the event of the internal resistance of the tube becoming so strong that also the natural period of the supplementary translator is located in the selective amplifying range, then it will

prove expedient to connect at this point a suitable resistance in parallel to the secondary coil S_1 , similar to resistance W .

Fig. 5 discloses a series connection of three amplifier tubes R_1 , R_2 , R_3 arranged on the same principle. In accordance with my invention, resistances W_1 , W_2 , W_3 are connected in parallel to the secondary windings S_1 , S_2 , S_3 of the translators U_1 , U_2 , U_3 .

10 The effect produced by this connection is, with the exception of the damping action introduced by the resistances, the same as in the case of the series connections of this kind already known, so that no further explanation will be required.

In the place of ohmic resistances alone, other damping means, such, for example, as oscillating circuits arranged in parallel to the secondary coils of the translators U , may 20 also be made use of, the inductance L and capacity C of these circuits being disposed in series as indicated in Fig. 4^a which may or may not include a resistance W .

Fig. 6 discloses a series connection of three amplifier tubes R_1 , R_2 , R_3 , arranged in accordance with my invention, in which the selectivity of the translators is distributed over the entire frequency range. As shown and similar to the arrangement of Fig. 5, 30 the heating battery B_1 and the anode battery B_2 are common to all the tubes.

In accordance with my invention, the capacities C_1 , C_2 , C_3 are connected in parallel to the secondary coils S_1 , S_2 , S_3 of the translators U_1 , U_2 , U_3 , which capacities are so chosen, for example, that the natural period of circuit S_1 , C_1 has a frequency of 3000, that of S_2 , C_2 a frequency of 5000, and that of S_3 , C_3 a frequency of 7000. In parallel to 40 coils S_1 , S_2 are connected resistances W_1 , W_2 in order to damp the selectivity of the systems S_1 , C_1 and S_2 , C_2 and, at the same time, secure a uniform degree of amplification. In the case of the system S_3 , C_3 a resistance 45 of this kind is not provided in order to secure a more pronounced amplification of the frequency preferred by the selectivity of this transformer. From the aforesaid it will be obvious that by a suitable combination 50 of these means of connection any desired distortion of the strengthening curve may be secured.

I claim:

1. In an arrangement for amplifying currents of varying frequency in a line for transmitting speech and having a plurality of thermionic amplifiers in cascade connection, means for eliminating the distortions of said currents, comprising transformers for transmitting currents from the line to the amplifier respectively from one amplifier to the other, capacities connected in parallel with the secondaries of said trans-

formers, said capacities being suitably dimensioned so as to render each of the several transformers selective to a different frequency within the whole range of frequencies to correspondingly affect the current in the several stages of amplification to eliminate its distortion over the whole range of frequencies, the selected frequencies being substantially uniformly distributed over the desired range.

2. In an arrangement for amplifying currents of varying frequency in a line for transmitting speech and having a plurality of thermionic amplifiers in cascade connection, means for eliminating the distortions of said currents, comprising transformers for transmitting currents from the line to the amplifier respectively from one amplifier to the other, capacities connected in parallel with the secondaries of said transformers, said capacities being suitably dimensioned so as to render each of the several transformers selective to a different frequency within the whole range of frequencies, and ohmic resistances for attenuating the selectivity of one or more of said transformers in order to obtain a uniformly amplified current, the selected frequencies being substantially uniformly distributed over the desired range.

3. In an arrangement for amplifying currents of varying frequency in a line for transmitting speech, and having a plurality of thermionic amplifiers in cascade connection, means for eliminating the distortions of said currents comprising transformers for transmitting the currents from the line to the amplifier respectively from one amplifier to the other, a shunt connection to the secondary of each of said transformers, including a resistance, a self-induction and a capacity, the said three elements being suitably dimensioned so as to render each of the several transformers selective to a different frequency within the whole range of frequencies, to correspondingly affect the current in the several stages of amplification to eliminate its distortion over the whole range of frequencies, the selected frequencies being substantially uniformly distributed over the desired range.

4. Method of amplifying currents with in a range of varying frequencies through a plurality of stages including amplifiers and transformers disposed therebetween, consisting in rendering the transformers between the stages each selective to a definite different frequency within the total range, the selected frequencies being substantially uniformly distributed over the entire range.

In testimony whereof I affix my signature.

BRUNO GERHARD POHLMANN.
